UNITED STATES PATENT OFFICE.

FREDERICK A. SCHLOSSOW, OF DETROIT, MICHIGAN.

FLUSHING-VALVE AND CONTROLLING MECHANISM.

1,364,891.

Specification of Letters Patent. Patented Jan. 11, 1921.

Application filed April 7, 1919. Serial No. 287,968.

To all whom it may concern:

Be it known that I, FREDERICK A. SCHLOSSOW, citizen of the United States, residing at Detroit, county of Wayne, State of Michigan, have invented a certain new and useful Improvement in Flushing-Valves and Controlling Mechanism, and declare the following to be a full, clear, and exact description of the same, such as will enable others skilled in the art to which it pertains to make and use the same, reference being had to the accompanying drawings, which form a part of this specification.

My invention relates to a flushing valve and its controlling mechanism, shown in the accompanying drawings and more particularly described in the following specification and claims:

One object of this invention is to eliminate the usual rubber ball with its attendant objectionable features and to provide a device of simple and inexpensive construction which includes a disk valve for closing the discharge outlet, linked to a manually controlled operating lever, — from which is suspended a weight adapted to function automatically to return the valve to its seat following the manual operation of the valve to secure the discharge of water from the tank,—said weight however, not becoming effective to close the valve until the water is substantially discharged from the tank.

Another feature of the invention is the variable weight employed to return the valve to its seat, consisting of a relatively small tank,—filled with water at all times—suspended from one arm of the manually controlled operating lever, which when submerged in the water of the flushing tank loses its effectiveness as a weight to control the action of the valve, but which upon the water being discharged from the tank through the operation of the manually controlled lever down to a level that will admit of the small water filled tank again becoming operative as a weight serving to immediately cause the valve to return to its seat that the flushing tank may be again filled with water.

With the foregoing and other objects in view which will hereafter appear, the invention resides in the combination and arrangement of parts and in the details of construction herein described and claimed,

it being understood however, that changes may be made in the precise embodiment of the invention herein disclosed without departing from the spirit of the same.

In the drawings accompanying this specification and forming part thereof:—

Figure 1 is a longitudinal vertical sectional view through a flushing tank with a portion of the tank broken away,—showing the flushing valve seated and the tank filled with water:—also the mechanism for controlling the operation of the valve.

Fig. 2 is a similar view showing the valve raised, and the water discharged down to a level which will cause the weight, serving to automatically seat the valve, to function immediately.

Fig. 3 is a perspective view of the lever operating mechanism controlling the flushing valve in the position shown in Fig. 2,— or as it would appear when the flushing valve is raised.

Fig. 4 is a perspective view of the valve, weight and lever operating mechanism as shown in Fig. 1,—or as it would appear with the valve seated.

Fig. 5 is a detail sectional view showing the adjustable screw for limiting the "throw" of the rocking lever and indicating in dotted lines the position of the arms and C' when the valve is in open position.

Referring now to the letters of reference placed upon the drawings:—

A, denotes a flushing tank. B, is a bracket secured to a ledge or other suitable device, in the side wall of the tank. C, indicates a rocking lever, having projecting lugs D, D, pivoted to the bracket B.

E, is a crank arm at one end of the lever to the end of which is secured a suitable chain or link connection F,—extending down through a pocket A', at one end of the tank,—fitted with a knob G, for the manual operation of the lever.

H, indicates a flushing valve of disk type, suspended from the opposite end of the rocking lever C, by a link I, having an eye J, loosely embracing the end of the lever.

C', denotes an arm, provided with a series of perforations C², projecting horizontally from the rocking lever C, when the latter is in the position shown in Figs. 2 and 3 of the drawings.

K, indicates a relatively small tank or can (adapted under certain conditions to

serve as an operating weight) suspended by a rod L, from the projecting arm C' of the rocking lever,—the rod being provided with a hook at the upper end that it may more readily enter one of the several apertures C², provided for its reception. K', indicates an opening in the tank through which it may be filled with water, and K², denotes a swinging cover for said opening to protect the water from spilling. B', indicates an upstanding lug, preferably integral with the bracket B, in which is supported an adjustable screw M, adapted to regulate the degree of "throw" of the rocking lever C.

Having indicated the several parts by reference letters, the construction and operation of the device will be readily understood.

For the purpose of this description, it will first be assumed that the valve is seated and the flushing tank filled with water as indicated in Fig. 1, the position of the valve operating mechanism being the same as shown in Fig. 4.

To discharge the water from the tank, the flushing valve is raised by manually pulling down knob G, connected with the rocking lever C, thereby tilting the latter into the position indicated in Figs. 2 and 3 of the drawings,—the degree of the "throw" being regulated by the adjustment of the screw M.

The can or tank K,—filled with water at all times,—is also raised simultaneously with the valve but being submerged in the water of the tank will not function to return the valve to its seat until the water level in the flushing tank is lowered sufficiently for the water filled can to become operative, whereupon it will cause the lever C, to rock thereby returning the valve H, to its seat.

It will now be seen that the closing of the flushing valve H, is entirely automatic and is contingent upon the discharge of water from the flushing tank, before the water filled tank K, can function to operate the rocking lever. The leverage due to the weight may be regulated by entering the end of the rod, from which the tank K is suspended,—in any one of the several apertures C², provided in the arm C', of the rocking lever.

It will be apparent that when the flushing valve is manually raised, the arm of the rocking lever from which the valve is suspended, will rock from one side of the pivoted axis of the rocking lever to the opposite side of the pivoted axis of the rocking lever;—the weight of the valve itself thereby becoming effective to maintain the valve in its raised position until reversed through the action of the water filled tank acting as a weight.

I claim—

1. In a device of the character described, a flushing tank, a rocking lever, a flushing tank valve suspended from the rocking lever

the point of suspension of the flushing valve being carried from one side of the fulcrumed lever to the other by the rocking of said lever, and a water filled tank also suspended from the rocking lever adapted to be raised simultaneously with the lifting of the flushing valve through the manual operation of the rocking lever but not enough to carry the point of attachment to the other side of the fulcrum, whereby upon the water being discharged from the flushing tank below the level of the suspended water tank the latter will function as a weight to return the flushing valve to its seat.

2. In a device of the character described, a flushing tank, a rocking lever, means for manually operating the rocking lever, adjustable means for regulating the throw of the rocking lever, a flushing valve suspended from the rocking lever, the point of suspension of the flushing valve being carried from one side of the fulcrum of the lever to the other by the rocking of said lever, and a tank to be filled with water that may function as a weight also suspended from the rocking lever and adapted to be raised simultaneously with the lifting of the flushing valve through the manual operation of the rocking lever but not enough to carry the point of attachment to the other side of the fulcrum whereby upon the water being discharged from the flushing tank the weight of the water filled tank will become operative to seat the flushing valve.

3. In a device of the character described, a flushing tank, a rocking lever having a projecting arm provided with a plurality of holes, a tank to be filled with water, a link adapted to enter any of the several holes in the projecting arm of the lever for adjustably suspending said last named tank therefrom, a flushing valve also suspended from the rocking lever, the point of suspension of the flushing valve being carried from one side of the fulcrum of the lever to the other by the rocking of the said lever, said water filled tank being adapted to be raised simultaneously with the lifting of the flushing valve through the manual operation of the rocking lever but not enough to carry the point of attachment to the other side of the fulcrum, and means for manually operating the rocking lever whereby the flushing valve and the water filled tank may be simultaneously raised so that the water filled tank may operate as a weight to return the flushing valve to its seat upon the discharge of water from the flushing tank.

4. In a device of the character described, a flushing tank, a rocking lever, a flushing valve suspended from the rocking lever, the point of suspension of the flushing valve being carried from one side of the fulcrum of the lever to the other by the rocking of the lever, a tank suspended from the rocking

lever and adapted to be raised simultaneously with the lifting of the flushing valve through the manual operation of the rocking lever but not enough to carry the point 5 of attachment to the other side of the fulcrum, said last named tank having an opening through which it may be filled with water whereby it may function as a weight,

and a cover for closing the opening in the last named tank. ¹⁰

In testimony whereof, I sign this specification in the presence of two witnesses.

FREDERICK A. SCHLOSSOW.
